CASTING APPARATUS

Albert Henry Jung, Flushing, N. Y., assignor to
United American Metals Corporation, Brook-
lyn, N. Y., a corporation of New York

Application June 25, 1938, Serial No. 215,909

7 Claims. (Cl. 22—94)

This invention relates to casting apparatus and more particularly to a casting apparatus wherein means is provided for ejecting the material cast from the apparatus.

5 Prior to my invention various arrangements have been proposed to effect ejection of ingots from molds which have been costly to produce, short lived, and generally inefficient and unsatisfactory. For example, it has been proposed 10 that molds including ejection apparatus be provided with cam means for effecting motion of such ejection apparatus. These arrangements have generally been short lived, requiring much service and attention, and found to be unsatisfactory for designs including cam operated ejection mechanism, inevitably involve the setting 15 up of stresses along lines at variance with the movement of the ejector elements in the mechanism which stresses make for excessive wear 20 and if the apparatus incorporating such design is to last a reasonable time the parts of same must be fabricated of relatively heavy material which is costly.

Various other ejector mechanism have been 25 proposed which have been found wanting for other reasons including unsatisfactory operation in that the material cast was not always ejected properly unless a relatively great amount of force was exerted by the operator or operating 30 motor which force after repeated operation of the machine, soon wrecked the same or the machine had of necessity to be made of excessively strong parts to resist the effects of these relatively great forces, which resulted in an expensive 35 design.

It is an object of this invention to provide a mold mechanism including ejection apparatus of simple, inexpensive, though rugged design.

It is a further object of the invention to provide 40 a mold mechanism including ejection apparatus of the type involving a minimum of stresses, resulting in lightness of parts, and the property of being long lived.

Other objects and the nature and advantages 45 of the invention will be apparent from the following description taken in conjunction with the accompanying drawings, wherein:

Fig. 1 is a view in elevation of my mold apparatus with the front cover plate removed including ejection mechanism;

Fig. 2 is a fragmentary view in elevation with the ejector mechanism in a different position from that shown in Fig. 1;

Fig. 3 is a view in perspective of the apparatus with the front cover plate in place; and,

Fig. 4 is a sectional view taken along lines 4—4 of Fig. 3 looking in the direction of the arrows.

Referring to the drawings, a back geared reversible motor 10 is associated in driving relation with the pulley 11 through the gear box 12 whereby rotation of the pulley 13 may be effected through the medium of V-belt 14. Directly connected to the pulley 13 is the shaft 15 having a series of left hand screw threads 16 and a series of right hand screw threads 17, respectively, formed thereon. The shaft 15 may be suitably supported by the frame 18 carrying ball bearings 19 and 20, respectively, which tend to reduce frictional losses and within which the 15 said shaft 15 rotates.

Fixed to the frame 18 at each end are the elements 21 to which are pivotally secured at 22 the links 23. Pivotally secured to the opposite ends 24 of the links 23 are the bars 25 which 20 are further pivotally secured at their respective ends 26 to the nut like elements 27 and 28, respectively, which are internally threaded to correspond with the left hand screw threads 16 and the right hand screw threads 17, respectively. 25 The opposite ends of the links 23 are pivotally secured by pins 29 to the ejector bar assembly which may comprise channel member 30 of a section of high radius gyration, ejector pins 31, and mechanism 32 performing the dual function 30 of securing the pins 31 to the channel member 30 and providing for adjustment of position of the pins with respect to the channel member. Secured to the upper portion of the frame 18, a mold proper 33 may comprise a series of cavities 35 34 having bores 35 formed therein through which the ejector pins 31 are adapted to pass and operate to loosen and eject castings therefrom.

Secured to the angle iron 36 of the frame 18 may be a pair of switch mechanisms 37 and 38 40 which are normally urged to closed circuit position but which are adapted to be operated to break the motor circuit and cause cessation of operation of the motor 10 by physical contact of the extending portion 39 of the nut like element 45 27 with the operating levers 40 and 41 of the switches 37 and 38, respectively.

The nut like elements 27 and 28 may be provided with adjustable stop contact nuts 42 to prevent injury to the machine should the switch 50 38 fail to operate or for any other reason. To insure that the mold proper 33 be held in level position, which is essential to the casting process, level adjusting means 43 may be associated with the frame 18 at the lower four corners thereof. 55

A manually operated multiple switch S is provided on the frame 18 at a location convenient to the operator of the machine by means of which initiation of the operation of the motor 10 5 may be effected, after the mold 33 has been filled with the material to be cast, and after the material has sufficiently solidified, whereby the link 25 will take the position illustrated in Fig. 2, the shaft 15 being rotated effecting axial movement of the nut like element 27 in a direction tending to effect vertical straightening out of the said link 25, whereby the pin 29 always remains directly above the pivot 22, though at increasing elevation, to effect movement of the 10 ejector pins 31 to their upper position as illustrated in Fig. 2. Further movement of the pins 31 is prevented by movement of the operating lever 40 associated with the switch 37 which effects opening of the said circuit. The castings 15 having been ejected from the cavities of the mold 33, the operator may then effect such movement of the switch S to close the circuit to the motor in a manner whereby rotation of the operating motor 10 in the opposite direction is effected and the nut like elements 27 and 28 will move toward 20 each other, bringing the pins 29 closer to the pivots 22 and the ejector pins 31 withdrawn to the position illustrated in Fig. 1. The motor 10, as has already been explained, is of the reversible 25 type and its circuits are so associated with the multiple switch S as to effect rotation of the motor 10 in one direction when the switch S is in one position and opposite rotation thereof when the switch is in a second position. Further 30 movement of the ejector pins 31 will be prevented by the opening of the circuit to the motor 10 by physical contact of the extension 39 of the nut like element 27 with the operating lever 41 of the switch 38 which will open the said circuit. The switch 37 is in that circuit of the motor 10 35 which effects its rotation in a direction to cause the ejector pins to move upwardly, and the switch 38 is in that circuit of the motor 10 which effects its rotation in a direction to cause lowering of the ejector pins. Both the levers 40 and 41 associated with the switch 37 and 38 respectively, are of the type that return to their normal closed 40 position when the motor-like element 27 is not in engagement therewith. The switch S being a multiple switch, one of its elements is in series 45 with switch 37 and another in series with switch 38. The switch 37 and 38 are normally closed, but may be opened automatically by the nut-like element 27, whereas the switch S is illustrated 50 as being manually operated. The cycle may again be repeated after the mold 33 has been filled with molten material and sufficient time elapsed for its solidification.

Referring to Fig. 3, the frame 18 may comprise 60 a pair of channel section legs 44, Z section corner members 45, cross pieces 46 associated with said corner members and adapted to be fabricated of a flat sheet by being slit at 47 whereby the portion 48 may be bent upwardly at right angles to the portion 49. A cover plate 50 is adapted to 65 cover the sides of the frame and is held in place by bolts 51. Cover plates 52 may be secured to the respective ends of the frame as illustrated in Fig. 3 to permit exposure of the working parts. Referring to Figs. 1 and 4, a series of four 70 angle irons 53 supported on cross members 54 are adapted to support the H beam 55 which extends from one end of the frame 18 to the other and which forms a base for the toggle mechanism already described which effects oper-

ation of the ejector pins to lift the solidified castings from the molds when desired.

While the shaft 15 is illustrated in Fig. 1 as being motivated by a belt driven mechanism, it is to be understood that it is within the scope of my invention that the said motor be directly connected to the said shaft 15 and a mounting may be so associated with the frame 18 as to support the motor in that position if such arrangement is preferred. It is further to be understood that conventional sprocket wheels, not shown, may be substituted for the pulleys 11 and 13 and a roller chain substituted for the belt 14, without deviating from my invention.

In order to insure rapid cooling of the mold proper 33, water pipe connections W and W' may be associated therewith whereby cooling water may be circulated through the jacket incorporated in the mold proper 33 as shown, see Figs. 1 and 3.

It will be seen from the above that the invention comprises a mechanism inexpensive to manufacture and capable of effecting desired results with the operating parts so arranged as to set up a minimum of undesired stresses and to effect positive ejection of the castings from the mold in the manner and when desired.

It will be obvious to those skilled in the art that various changes may be made in this device without departing from the spirit of the invention and therefore the invention is not limited to what is shown in the drawings and described in the specification but only as indicated in the appended claims.

I claim:

1. A casting apparatus including a mold and means for ejecting castings from said mold including an ejector element, means for imparting toggle action leverage to said element comprising a toggle mechanism, motor means for effecting 40 operation of said toggle mechanism, manual control means for forward operation of said motor means, means responsive to a predetermined position of said toggle mechanism for effecting cessation of operation of said motor means, 45 manual control means for effecting reverse operation of said motor means, and means responsive to another predetermined position of said toggle mechanism for again effecting cessation of operation of said motor means. 50

2. A casting apparatus including a mold, a frame for supporting said mold, means for ejecting castings from said mold comprising a toggle mechanism, said toggle mechanism including a driven shaft, a rider associated with said shaft, 55 said rider and said shaft each having formed thereon corresponding screw threads, a linkage arrangement pivotally associated with said rider and with said frame to effect straight line movement with toggle action leverage of a portion of 60 said linkage, an ejector pin associated with said portion and with said mold, all of said ejector means being supported by said frame and therewithin, a motor arranged to drive said shaft, manual control means for forward operation of 65 said motor, means responsive to a predetermined position of said ejector means for effecting cessation of operation of said motor, manual control means for effecting reverse operation of said motor, and means responsive to another pre- 70 determined position of said ejector means for again effecting cessation of operation of said motor means.

3. A casting apparatus including a mold, a frame for supporting said mold, an ejector mech- 75

anism associated with said mold and secured within and supported by said frame, said mechanism comprising a rotatable shaft having a section formed with left hand screw threads and a section formed with right hand screw threads, means for rotating said shaft, a rider associated with said left hand threads, a second rider associated with said right hand threads, an ejector bar, an ejector pin associated with said mold and secured to said bar in adjustable relation thereto, a first linkage arrangement pivotally associated with said bar, said frame, and said first rider, a second linkage arrangement pivotally associated with said bar, said frame, and said second rider in a manner whereby a portion of each linkage arrangement which is pivotally associated with said bar is adapted to be limited to straight line movement.

4. A casting apparatus including a mold, said mold comprising a plurality of cavities, means for ejecting a casting from each of said cavities including an ejector pin, means for supporting said pin comprising a bar having a section of high radius of gyration, a linkage mechanism associated with said bar, a portion of which is adapted to be limited to straight line motion, said portion being pivotally secured to said bar, motor means for effecting operation of said linkage arrangement, manual control means for initiating operation of said motor, means responsive to a predetermined position of said linkage arrangement for effecting cessation of operation of said motor.

5. Ejector mechanism for metal mold apparatus comprising a frame, a rotatable threaded shaft journaled in said frame, an unrestrained freely movable toggle mechanism comprising a first link and a second link pivotally secured together at the end of one and at an intermediate portion of the other, a threaded rider in slidale engagement with said threaded shaft, one of said links being pivotally secured at one of its ends to said rider, the other of said links being pivotally secured at one of its ends to said frame, the sizes of the respective links and the positioning of the common pivot of the links being cooperatively related to effect movement of the free end of one

of said links in a straight line in proportion to the motion of the rider, an ejector bar pivotally secured to the said free link end, said ejector bar being of a section having a high radius of gyration, an ejector pin secured to said ejector bar, and means for freely rotating said shaft and effecting movement of said ejector pin indirectly through the toggle mechanism.

6. A casting apparatus including a stationary mold, a rigid frame for supporting said mold in a horizontal position, means for ejecting castings from said mold including a plurality of ejector pins, means for moving said ejector pins including a toggle mechanism directly associated therewith and operative to continuously apply toggle leverage to said ejector pins, said toggle mechanism comprising a driving end and a driven end, said toggle mechanism including a relatively large link and a relatively small link, a first end of said small link being pivotally connected midway between the extremities of said large link, one end of said large link being drivingly associated with the ejector pins, the second end of said small link being pivotally connected to a motor means, the size of said small link corresponding to the distance between the common pivotal connection between the two links and either of the extremities of the large link whereby the horizontal straight line motion of said motor means will effect vertical straight line motion of said toggle.

7. In a casting apparatus, a relatively heavy mold, relatively light ejector means, said relatively heavy mold being stationary, said relatively light ejector means being movable, single toggle means for moving said ejector means through a portion of said mold, said single toggle means being characterized by a driving end and a driven end, means for effecting movement of said driven end, said toggle means being further characterized by its capacity for effecting independent straight-line movement of its driven end, whereby castings may be ejected from said relatively heavy mold by relatively unguided and independent light mechanism.

ALBERT HENRY JUNG.
